Attorney

UNITED STATES PATENT OFFICE.

BRUCE CONKLIN, OF LONDON, ENGLAND.

ROTARY ENGINE.

1,326,252.

Specification of Letters Patent. Patented Dec. 30, 1919.

Application filed September 28, 1917. Serial No. 193,677.

To all whom it may concern:

Be it known that I, BRUCE CONKLIN, a citizen of the United States of America, residing at London, in the county of Middlesex, England, have invented a new and useful Improvement in and Relating to Rotary Engines, of which the following is a specification.

This invention has reference to rotary engines, pumps, compressors, and like devices of the kind comprising concentrically mounted elements relatively movable in an angular direction one of said elements having a plurality of vanes and other or others of said elements a plurality of rotary abutments the annular space or spaces between the elements constituting the working chamber or chambers. The primary object of the present invention is to provide improved means for maintaining a fluid-tight joint between certain of the moving parts in contact during running. Further objects are to eliminate any tendency on the part of the aforesaid rotary abutments to move laterally or partake of an uneven torque during running, to minimize friction between the ends of the rotary abutments and the element in which they are mounted, to provide for efficient lubrication of the parts and generally to improve the construction and mounting of certain parts of a rotary engine of the afore-mentioned type whereby the engines may be rendered more efficient in operation.

More particularly the invention is designed to provide improvements in the construction and operation of rotary engines, pumps, compressors, and like devices of the kind described in my prior specifications Serial Numbers 153903 and 153904 and reference to such specifications will facilitate the ready understanding of the present improvements, although I do not desire to be understood as limiting the present invention to the engines described as it is equally applicable to engines of the rotary abutment and annular chamber type provided with more than one annular working chamber.

With the aforesaid objects in view and such others as may hereinafter appear or are incidental thereto my invention in its broadest aspect may be said to be embodied in a construction of the aforesaid kind in which the rotary abutments are arranged in such a manner that the ends thereof are embraced

by or housed in a portion of the element in which they are rotatably mounted while the pocket in each of said abutments which allows the vanes of the rotating concentrically mounted element to pass from one side of said abutments to the other during rotation of the engine is closed at each end.

Further and subsidiary features of the invention reside in the improved construction and arrangement of the packing rings and strips which are employed to maintain fluid tight joints between the moving parts in contact during running and in the provision of improved means for insuring adequate lubrication of the moving parts.

In order that my invention may be readily understood and carried into effect by those skilled in the art to which it appertains, I will now proceed to describe the same fully with reference to the accompanying drawings in which:

Figure 1 illustrates in vertical section a rotary steam engine embodying the present invention.

Fig. 2 is a section of the inner drum.

Fig. 3 represents a longitudinal section of one of the rotary abutments.

Fig. 4 is a fragmentary sectional view, showing a plurality of abutments and a plurality of vanes.

In that embodiment of the invention illustrated the drum A (Fig. 2) is cast in two parts 1 and 2 and bolted together accurate registration being insured by a spigot 3 and the construction is such that a recess 4 is formed around the periphery of the drum which recess constitutes the annular working chamber when the drum is in position within the outer casing 5 (Fig. 1).

The drum A is recessed at a plurality of points to accommodate a plurality of rotary abutments 6 to be hereinafter described one of said recesses being shown at 7 (Fig. 2) and it will be observed that when the rotary abutments 6 (Fig. 1) are in position the ends thereof are embraced by and housed in the side walls *a* and *b* of the drum A in contradistinction to the arrangement illustrated in my prior specification above referred to where a portion of the ends of the rotary abutments were in contact with the outer rotating casing with the consequence that a considerable amount of friction occurred between the ends of the rotary abutments and the rapidly rotating outer casing.

By the means hereinbefore detailed this

friction is largely reduced as the rotary abutments turn in contact with the stationary sides *a* and *b* of the drum A. Moreover by forming the annular working chamber 4 in the periphery of the drum A and embracing the ends of the abutments by the side walls constituting such working chambers losses due to leakage of the working fluid will be reduced to a minimum.

- 10 The construction of the rotary abutments 6 which are mounted in the recesses 7 will be best understood by referring to Fig. 3 which represents a longitudinal section through one of said abutments. It will be seen that 15 the pocket 8 therein which allows the vane 9 (Fig. 1) to pass from one side of the abutment to the other during rotation of the outer casing 5 extends from side to side of the main body *c* of the abutment as is the 20 case in the construction described in my aforesaid prior specifications but according to the present invention there is secured to each end of the main body *c* a disk 10 so that the ends of the pocket 8 are closed and 25 as a consequence thereof leakage of working fluid past the end of the vanes during their passage through the pocket is largely prevented.

To still further reduce losses of working fluid during running of the engines I provide packing strips or piston rings 11 (Fig. 1) which are located in recesses on the periphery of the drum A and these strips or rings project over the annular edges of the 30 rotary abutments 6 as clearly shown in Fig. 1. Each of the vanes 9 is also provided with a packing strip 12 having flanges 13 abutting on the strips or rings 11 and maintained in contact therewith by spring bolts 14 or the 35 like while springs 15 located in housing in the vane 9 operate to keep the strip 12 in contact with the ends of the pockets 8 constituted by the disks 10.

A duct 16 (Fig. 1) is formed in the drum 40 A through which suitable lubricant may be supplied in any appropriate manner and other ducts 17, 18 and 19 serve to conduct said lubricant to the bearings of the rotary abutments and to the piston rings 11 from 45 which it finds its way to the pocket 8 to lubricate the vane. The disks 10 may be recessed as shown at *d* in Fig. 3 or concentric or other grooves may be provided therein to allow the lubricant supplied to the 50 rings 11 to creep between the disks 10 and the walls of the drum with which they are 55 in contact.

What I claim and desire to secure by Letters Patent of the United States is:

- 60 1. In a rotary engine, pump, compressor or like device the combination with an outer normally rotatable casing an inner normally stationary drum and an annular working chamber between the proximate 65 surface of the casing and drum of a plu-

rality of vanes in the outer casing traversing the said annular working chamber a plurality of rotary abutments mounted in said stationary drum, side walls on said drum extending to meet said outer casing and inclose the said annular chamber so as to house and embrace the ends of the said rotary abutments, a pocket in each of the said rotary abutments to receive the vanes and allow the latter to pass from the one side of said 70 abutments to the other during the working of the engine, closing means at each end of said pockets, means for introducing working fluid to the interior of the drum and to the annular working chamber and means for exhausting the low pressure fluid therefrom.

2. In a rotary engine, pump, compressor or like device the combination with an outer normally rotatable casing, an inner normally stationary drum and an annular working 85 chamber between the proximate surfaces of the said casing and drum, of a plurality of fixed vanes in the inner side of the outer casing traversing the said annular working chamber, a plurality of rotary abutments mounted in said stationary drum, side walls on said drum extending to meet the said outer casing and inclose the said annular chamber so as to house and embrace the ends of the said rotary abutments, a 90 pocket in each of said rotary abutments to receive the vanes and allow the latter to pass from the one side of said abutments to the other during the working of the engine, a plate having grooves or channels on the outer face at each end of the said pockets for closing the same, means for introducing working fluid to the interior of the drum and to the annular working chamber and means for exhausting the low pressure 100 fluid therefrom.

3. In a rotary engine, pump, compressor or like device, the combination with an outer normally rotatable casing having a plurality of vanes, of an inner normally stationary 110 drum having a plurality of rotary abutments, an annular working chamber in the periphery of said drum, a plurality of rotary abutments mounted with their ends embraced by the walls of the drum forming 115 the annular working chamber, a pocket in each of said rotary abutments, means for closing the ends of said pockets, piston rings on said drum coöoperating with the casing and the edges of said rotary abutments to 120 maintain a fluid tight joint, means for the introduction of working fluid to the annular working chamber, and means for exhausting the low pressure working fluid.

4. In a rotary engine, pump, compressor 125 or like device, the combination with an outer normally rotatable casing having a plurality of vanes, of an inner normally stationary drum having a plurality of rotary abutments, an annular working chamber in the 130

BRUCE CONKLIN.
